UNITED STATES PATENT OFFICE.

KARL ALBERT FROSELL, OF NEW YORK, N. Y.

MOVABLE SCAFFOLD.

SPECIFICATION forming part of Letters Patent No. 508,378, dated November 7, 1893.

Application filed January 18, 1893. Serial No. 458,852. (No model.) Patented in England August 18, 1892, No. 14,939.

To all whom it may concern:

Be it known that I, KARL ALBERT FROSELL, a resident of New York, in the State of New York, having declared my intention of becoming a citizen of the United States of America, have invented certain new and useful Improvements in Movable Scaffolds or Traveling Platforms, (for which I have obtained a patent in Great Britain and Ireland, No. 14,939, dated August 18, 1892;) and I do hereby declare that the following is a full, clear, and exact description of the invention, reference being made to the accompanying drawings, which are to be taken as part of this specification and read therewith, which will enable others skilled in the art to which it appertains to make and use the same.

This invention relates to improvements in movable scaffolds or platforms, such as are used by bricklayers, masons, painters and others engaged in dressing and pointing the external faces of walls, or in painting the frames of the windows and doors therein.

It consists in improved devices for raising and lowering the movable scaffold with a climbing action and motion, as well as for shifting the scaffold laterally for the purpose of bringing it in front of another width of work.

Figure 1 is a sectional side elevation illustrating the construction of my apparatus. Fig. 2 is a detail sectional side elevation on the line 2—2 of Fig. 3 omitting the raising and lowering levers. Fig. 3 is a sectional front elevation omitting the disengaging gear. Fig. 4 is a front elevation illustrating more particularly the process of shifting a scaffold pole. Fig. 5 is a plan of the shifting strut and the guide for the shifting rope. Fig. 6 is a sectional plan of the top roller guide closed. The dotted lines show it open. Fig. 7 is a rear elevation of the same guide closed, omitting the rollers. Fig. 7^a is a detail rear elevation, partly in section, of the top of the

hollow pole, the head-pole, and the adjacent portion of the safety rope, its compressors, and their rope. Fig. 8 is a front elevation of a two pole movable scaffold. Fig. 9 is a front elevation illustrating a modified form of claw to be used with a notched bar on the hollow pole. Fig. 10 is a side elevation correspond-

ing therewith. Fig. 11 is a sectional plan taken along line 11—11 of Fig. 10. Fig. 12 is a front elevation illustrating a modification of the bar illustrated in Figs. 1 to 4 and Fig. 5. Fig. 13 is a sectional plan on the line 13—13 of Fig. 12. Fig. 14 is a front elevation of a modification of the claw and notched bar illustrated in Figs. 9, 10 and 11. Fig. 15 is a side elevation corresponding therewith. Fig. 16 is a sectional plan on the line 16—16 of Figs. 14 and 15.

a is the bottom scaffold pole; and *b*, the head pole or capital. Both of these are square in cross section the former for the purpose of preventing the hollow pole next described turning upon it; and the latter, to prevent it turning within the hollow pole. This latter, *c*, is, as heretofore, a square tube of a proper size to fit and slide up or down the pole *a* and to receive the pole *b* socketwise. Its ends are protected by ferrules *c'*.

The heel of the bottom scaffold pole is shod with a metal shoe. This consists of a ring *a'* and four arms *a''*. The latter meet at a right angle with each other at a point under the center of the ring and are bent upward in a circular direction and made fast to the side of the ring symmetrically. Each arm is continued past the ring and terminates in an eye *a'''*. The shoe is made fast to the heel of the pole, with the eyes *a'''* standing substantially parallel with the four faces of the pole respectively.

a⁴ is a movable base block. A central cavity *85* is formed in the top face of a proper size to receive as much of the shoe as is necessary to prevent the pole slipping. The sides of this cavity are concaved to the same arc as the arms *a''* are bent to.

a⁵, *a⁶* are a series of equidistant and equal holes formed in the pole *a* and extending through from front to back, and *a⁶* is a strong pin of the right section to fit easily therein and long enough to project beyond both the front and back faces of the hollow pole *c*.

The head pole *b* projects downward into the hollow pole *c* far enough to keep it steady in and on it. Its projection above it is used to carry part of the shifting devices and is maintained by the straps described farther on resting upon the top of the hollow pole *c*.

The three poles thus fit together in such a way that they are virtually one, and the base-block a^4 and the shifting gear described farther on, acting together, suffice to maintain 5 the composite pole in a vertical position.

The movable scaffold consists of a strong floor d , corner uprights d' a hand or safety rail d^2 carried by them, such additional horizontal rails as may be desirable, a subsidiary floor d^3 hinged to the front side of the floor and adapted to make it up to the wall, and telescope handrails d^4, d^4 . These latter slide backward and forward through eyes d^5 . Each eye has a screwed shank which passes 15 through the respective hand rail d^2 and carries on its inner end a wing nut by which the rail d^4 can be held in any position. The subsidiary floor d^3 , and the two rails d^4 , when they are out as far as the wall, *i. e.*, in the position illustrated in Fig. 1, serve to steady the composite scaffold-pole and the scaffold.

d^6 is a hole in the floor d large enough to allow the hollow pole c to pass through. The scaffold as a whole is held to the said pole, 25 and its steady motion up or down it is provided for by means of two roller-guides each of which embraces the pole. Each guide consists of a ring d^7 , preferably of angle iron, necessarily of the same contour as the hollow 30 pole c , and large enough to clear it as it moves up and down it, four rollers d^8 , their axles d^9 , and four pairs of webs d^{10} projecting vertically from the ring d^7 , the two of each pair forming a right angle with each other coincident 35 with the respective external angle of the ring, and in which webs the said axles have their bearings. The latter are so positioned in their webs that the rollers d^8 are all equally in contact with the pole c . So far the two 40 guides are alike in respect of construction and operation. The rear side of the top one is pivoted in the manner shown in Figs. 1, 6 and 7. The axle d^9 of this particular side has no bearing in either of the respective webs. 45 Instead thereof it projects through both webs, each end standing between a pair of horizontal webs d^{11}, d^{11} . One end of the axle terminates in an eye d^{12} .

d^{13} is a bolt passed downward through the 50 eye and the web between which it stands. This forms the pivot of the side in question. d^{14} is a stop-pin, which, by being passed through two holes in the opposite pair of webs d^{11}, d^{11} , in front of the axle, and after the latter has been pushed in between the webs, 55 closes the guide, and keeps the pivoted roller up to the respective face of the pole c . The bottom guide fits within the hole d^6 in the floor d . The top one is held at a suitable distance above it by three stays d^{15} , which spring 60 from the said floor.

e, e are a pair of vertical and parallel guide rods. Their top ends are made fast to the front side of the top guide, and their bottom 65 ends to a bridge-piece e' which is made fast

to the floor d . These two rods stand symmetrically right and left of the center line of the scaffold-pole.

e^2 is a stout slider. It is provided with four eyes e^3 , two on each side of it, which embrace 70 the respective guide rod e .

e^4 is a pin, fast to, and projecting centrally from, the front face of the slider.

e^5, e^6 are a pair of levers. They are counterparts of each other, and have a common 75 fulcrum in the pin e^4 , their handles standing on opposite sides of the fulcrum.

e^7, e^8 are two equal links. Each is pivoted by one end to the outer end of the respective lever e^5, e^6 , and by the opposite end to an eye 80 e^9 . The eyes e^9 are made fast to the floor d symmetrically right and left of the hole d^6 .

e^{10} is a metal bar mortised centrally into the front face of the pole c . In this bar and the pole behind it I form a series of equidistant and equal holes e^{11}, e^{11} , aligned vertically with each other.

f, f' are a pair of bell-crank levers. The former has its fulcrum in a pair of projections f^2 on the bottom face of the slider e^2 , and the latter in the top of a crutch f^3 which stands up from the bridge-piece e' between the guide-rods e . The shorter arms of these levers project to the front of the plane in which their fulcrums stand. The upper extremities of the 95 longer arms of the bell-crank levers f, f' terminate in claws f^4, f^5 , the faces of which are convex upward and backward from the pole. A claw face is deeper than a hole, so that when a claw is in its hole, the top of it is outside and above the hole and to the front of the plate e^{10} . In point of position these claws are always aligned with each other, and opposite the vertical center line of the post c . As to size, either of them is adapted to enter and 100 hold the scaffold suspended from any of the holes e^{11} . Suitable devices are provided for the purpose of forcing a claw into the holes whenever it is opposite any one of them. They are, preferably, of the spring type. 110 That of the top claw f is a loop f^6 the ends of which are wound round and made fast to the extremities of pins f^7 , while its operative end f^8 bears upon the back of the catch, and pushes it toward the pole c . The bottom claw 115 f' is kept up to the plate e^{10} , and forced into the holes e^{11} , whenever it is opposite to any one of them, by a spiral spring f^9 , which is made fast by one end to the short arm of the bell-crank lever f' , and by the other to an adjustable double socket f^{10} which is held fast 120 to the guide-rods above the fulcrum of the said lever. Any equivalent spring devices adapted to keep the claws in contact with the face of the pole and to drive them into the 125 holes when they are opposite to them, may be employed.

f^{11}, f^{11} are notches in forward extensions of the slider and the socket. They serve as guides for the claws.

The disengaging mechanism, which is brought into operation prior to lowering the scaffold is as follows:

5 g is a vertical cylinder pivoted near its bottom end on the outer end of the short arm of the bell crank lever f' .

g', g' are the cylinder ends.

g^2, g^3 are a pair of thimbles each of two diameters. By the larger of these they are

10 adapted to slide up and down the cylinder, and by the smaller, through the ends.

g^4 is a spiral spring permanently in compression. It is strong enough to keep both thimbles with their larger diameters up at the 15 respective ends of the cylinder.

g^5 is a rod fitting within, and adapted to slide in either direction through, the thimbles. The top end of it, and the outer end of the shorter arm of the bell-crank lever f , are 20 so made that they can be easily connected together or disconnected.

g^6, g^7 are two collars fast upon the rod g^5 , the latter to the bottom, and the former nearer the top. When the rod g^5 is at the top of its 25 stroke—the position illustrated by the full lines of Fig. 2—the distance between the thimble g^2 and the collar g^6 is a little less than that between the supporting faces of any two adjacent holes e^{11} .

30 b' is a frame fixed fast to the head-pole b , preferably to the rear face of it.

b^2, b^3 are a pair of compressors, each pivoted upon its own axis b^3 . Their operative surfaces are toothed.

35 b^4, b^4 are a pair of extensions, each one on the inner side of the compressor.

b^5, b^5 are a pair of springs fast by their upper ends to a ledge b^6 above the compressors, and by their lower ends to the respective extensions b^4, b^4 . The function of these springs is to rock the compressors outward and upward until they compress and hold the safety-rope fast against the top of the frame b'

40 b^7 is a rope bifurcated at one end. Each 45 fork of the rope is made fast to an extension b^4 .

The shifting strut as seen in Fig. 5 consists of a pair of arms b^8, b^8 which are fixed to the hollow pole c in the way described farther on, 50 and from which they project symmetrically to the rear thereof. Each arm is extensible by any suitable means. According to the construction illustrated, each arm b^8 has eyes b^9, b^9 projecting from it through which a second 55 arm b^{10} can be moved to and fro.

b^{11}, b^{11} are small antifriction wheels or rollers, carried by the outer ends of the arms b^{10} , and lying or projecting always in a horizontal plane.

60 b^{12}, b^{12} Fig. 5 are set-screws, carried by the arms b^8 , and serving to fasten the arms b^{10} or to release the same for adjustment.

b^{13}, b^{13} are braces from one arm b^8 to the other.

65 The strut is fixed to the pole c by means of a shackle b^{14} . This is made adjustable to any height on the pole by having one side detach-

able. The shackle is held to the pole by drawing the detachable side and the opposite side together by wing nuts b^{15} , engaging with the screwed ends of the shackle sides. The 70 arms b^8, b^8 are pivoted upon a pair of studs b^{16}, b^{16} projecting from the shackle sides.

b^{17}, b^{17} are stop-pins adapted to prevent the weight of the strut outside the pivots pulling 75 it down.

b^{18} is the safety rope.

b^{19}, b^{19} are two fixed points at about the same level as the head pole one on each side of the latter. They are preferably provided 80 by stout pegs driven into the cornice or parapet of the wall, as illustrated in Figs. 1 and 4.

b^{20} is an eye supported by two arms b^{21}, b^{21} , Fig. 5, in a central and stationary position in front of the vertical plane of the scaffold. These 85 arms are made fast to the head pole b just below the frame b' already described. b^{22} is a cleat. It is carried at the end of an arm b^{23} which projects from the foot of the hollow pole c to the vertical line of said eye b^{20} . The 90 shifting ropes b^{26} are represented as prolongations of the safety ropes b^{18} . Half of the whole rope is passed through the frame b' between the compressors and the frame top, and both halves are then made fast to the fixed 95 points b^{19}, b^{19} , respectively. In practice separate ropes may be employed. The shifting ropes are led from the said points toward the pole, downward through the eye b^{20} , and are made fast to the cleat b^{22} . The safety rope 100 is thus out of the way of mischievous individuals on the ground, who cannot get at it to injure it. The shifting ropes, too, hang outside the hollow pole instead of being led downward inside it and their cleats are on the 105 hollow pole instead of being at some distance from it. b^{24} is a hand lever; and b^{25} an upwardly pointing hook fast to its side near the front end of it.

The apparatus made as above described is 110 used as follows: The scaffold is set on the ground and the top-guide opened. The hollow and head poles, with the strut properly adjusted for distance from the wall, as well as to miss windows and the like, can now be 115 set up through the open side of the top-guide without letting them down through it, or lifting the scaffold over the hollow pole. The bottom pole a with its pin a^6 in the proper hole is then got into position, and the shifting ropes b^{26}, b^{26} , made taut to their cleat b^{22} . Both claws f, f' are in as many holes e^{11} in the face of the hollow pole, and the levers e^5, e^6 in the position No. 1 shown by the full lines of Fig. 3. To raise the scaffold up the 120 pole c , (assuming that the levers stand in position No. 1, Fig. 3,) the rod g^5 is unfastened from the bell-crank lever f . The levers e^5, e^6 are next raised from the position No. 1 to position No. 2. This raises the slider e^2 up 125 to the top of the guides, and consequently pushes the top claw f^4 out of the bottom hole but two—see the dotted lines of Fig. 2—and leaves it opposite the next hole above, into

which it is forced by the spring f^6 . The vertical motion of the slider suffices to disengage the claw from the hole because its front edge is convex upward and backward and the top 5 of it was outside the hole and above it. During the time that the claw f^4 is passing from one hole to the one above it, the scaffold is suspended by the claw f^5 . The levers are then pulled down into position No. 3, with the 10 result that the scaffold is lifted the distance of one hole into the position indicated by the dotted lines of Fig. 3. During this lift, the claw f^5 is disengaged from the hole in which it was, and engaged in the one above by the spring 15 f^9 pulling its shorter arm up. A double motion of the levers lifts the scaffold the distance separating two holes. To lower the scaffold down the pole, (assuming that the levers stand in position No. 2 of Fig. 3, the 20 corresponding position of the scaffold being the one illustrated by the full lines of Fig. 2,) the rod g^5 is connected to the short arm of the bell-crank lever f . The immediate result is that the thimbles g^2 , g^3 are pulled into the 25 position illustrated in Fig. 2 by the washer g^7 and the spring g^4 acting together. The handles of the levers are next pressed down a little, just enough to take the weight of the scaffold off the top claw f^4 which is forthwith 30 pulled out of its hole by the spring g^4 acting upon the thimble g^3 and using the other thimble g^2 as a base of operation. The levers are then pushed toward the position No. 1, Fig. 3, whereupon the weight of the scaffold pulls 35 it down until the claw f^4 is opposite the next lower hole, when it is forced into the same by the spring f^6 . During the descent of this scaffold, the claw f^5 remains in its hole. The new position of the top claw and of the 40 engaging gear is indicated by the dotted lines of Fig. 2 and by the full lines of Fig. 3. The washer g^7 has been carried down away from the cylinder, and the collar g^6 brought down low enough to exert some pressure upon the 45 cylinder top g' . The levers, now standing in position No. 1, Fig. 3, are again pressed down a little, partly to take the weight of the scaffold off the claw f^5 , and partly to increase the pressure upon the cylinder top. The said 50 claw is forthwith pushed out of its hole by the rock of the bell-crank lever f' upon its fulcrum in the top of the crutch f^3 , which rock is caused by the said pressure, into the position indicated by the dotted lines of Fig. 2. 55 The weight of the scaffold once more pulls it down the pole until the claw f^5 is opposite the next lower hole. During this descent, the claw f^4 remains in its hole, and the rod g^5 is stationary. The projecting thimble g^3 60 comes into contact with the washer g^7 , and is, with the spring and the thimble g^2 , pushed up into the position illustrated by the full lines of Fig. 2; the bell-crank lever f' is rocked on the pivot in the top of the crutch f^3 , and 65 the claw f^5 is forced into the said next lower

hole. The levers are now in position No. 2, Fig. 3.

It is a matter of indifference in which of the two positions the levers may be when the scaffold has to be either raised or lowered. 70 They are started to the other position, the corresponding claw being either disengaged raised and forced into a higher hole, or disengaged, lowered and forced into a lower hole as the case may be. 75

Either or both of the levers e^5 , e^6 may be worked, in raising and lowering the scaffold as above; both levers being connected in like manner with the slide e^2 , which carries the bell-crank lever f , which in turn carries said 80 claw f^4 . See Fig. 3.

To shift the scaffold to either hand, e. g. to the right hand, (this operation being understood from a reference to Figs. 3, 4 and 7^a.) the compressors b^2 are pulled away from the 85 safety rope by pulling the rope b^7 . The position which the compressors will then occupy is illustrated by the dotted lines in Fig. 7^a. The pendent or shifting ropes, b^{26} , b^{26} , are loosened from their cleat b^{22} , and, after their ends 90 have been carried to the right hand of the pole, the right hand one is hauled on. The hauling is from the right hand peg b^{19} ; consequently the head of the pole is pulled over along the safety rope b^{18} into the position illustrated by the dotted lines of Fig. 4, the other rope b^{26} being paid out as much as its fellow is hauled in. The hook b^{25} on the side of the hand-lever b^{24} is then engaged in either the front or rear eye a^3 of the pole-shoe, and the 95 extremity of the short arm brought to rest upon the ground to the right hand of the base block a^4 , the longer arm standing up on the left hand. Power is applied to the last mentioned arm, and the block levered along until 100 it is vertically under the head of the pole. The ropes b^{26} , b^{26} are then made fast to their cleat, and the rope b^7 slackened till the compressors b^{12} , b^{12} hold the safety-rope between themselves and the top of the frame b' . When 105 the pole is pulled over, the head is of course brought lower, and when the base-block is moved the head is raised again. The pivotal connection of the shifting strut to the pole provides for its accommodating itself to both 110 of these motions of the pole-head. 115

A scaffold to work on a single pole is necessarily limited in point of length. When it is desirable or necessary that that limit of length be exceeded, a twin pole modification 120 is made use of. This modification is illustrated in Fig. 8. The same references are used as with the single pole construction. The differences in detail are as follows:

The base block a^4 .—This is long enough to 125 provide cavities for both the poles. It is shifted by using a lever to each pole at the same time.

The levers e^5 , e^6 .—There is only one to each slider. But the longer arms of both stand 130

toward each other and are linked together by any suitable device, *e. g.* a stud e^{12} , projecting from the side of one of the levers near the outer end and engaging in a slot e^{13} in the other lever.

5 *The shifting strut.*—One arm and roller are fixed to the outside of each pole c , and the detachable side is long enough to engage all the four screwed ends of the sides of the two shackles b^{14} . The braces b^{13} are lengthened accordingly.

10 *The shifting gear.*—The eye b^{20} is unsupported preferably in a central position between the two poles. The rope b^7 also occupies a central position. It is bifurcated three times, once to respective poles, and each fork once to the respective compressors. The cleats for the three ropes b^7, b^{26}, b^{26} are fixed in any convenient position.

15 20 The scaffold may be as long as would make the use of more than two poles desirable. But no matter how many poles are used there is only one base block and one shifting gear common to them all, for they must all be moved at once.

25 It must be distinctly understood that although the hollow pole is the one up or down which, according to my invention, the scaffold climbs with a one-before-the-other clawing motion and action, I do not limit myself to the minor details of the construction of the claw and of the bar to which it clings, but may use any one which may be suitable. For instance, according to the construction illustrated in Figs. 9 to 11, the flat recessed bar e^{10} with its series of equidistant holes e^{11} is replaced by a T-bar e^{14} . The flanges of it are recessed flush with the face of the pole c from which the web e^{19} projects at a right angle. 30 e^{15}, e^{15} are a series of equidistant notches cut therein. These notches are inclined downward from the front edge of the web, and backward toward the flanges. The longer arm of the bell crank lever has a pair of forwardly extending webs e^{16}, e^{16} , formed upon it. These webs stand apart far enough to allow of their embracing the web of the bar which serves as a guide for the lever. e^{17} is a pin extending from web to web of the claw, 35 and near enough to the front edges of the latter to allow of it resting in the bottoms of the notches, which are shaped to correspond.

40 The construction illustrated in Figs. 12 and 13 is characterized by the use of a channelled bar e^{18} fixed flush with the face of the scaffold. It has equidistant holes, e^{11} , in it, in the same way as has the bar e^{10} . The channel serves as a guide for the claws f^4, f^5 , and in so far replaces the notches f^{11} .

45 50 In Figs. 14, 15, and 16, the bar is of T-section, with duplicate webs e^{19}, e^{19} . It is notched in the same way as the bar e^{14} . The long arm of the bell-crank lever rides up and down the channel between the two webs, which therefore act as guides. The pin e^{17} is passed

through its nose at right angles with it, from which it projects right and left.

I claim—

1. The combination of movable scaffold, scaffold pole or poles, a vertical series of equidistant holes or detents on the face of the pole, a claw pivoted upon a block movable vertically with reference to the scaffold by levers connected with the scaffold, and a second claw pivoted on a fixed attachment to the scaffold, spring devices adapted to drive the claws into the holes or notches against which they may respectively be, and a detachable connection between the two claws consisting of a spiral spring held within a cylinder, thimbles projecting from the ends thereof, a rod releasably connected to one claw and adapted to move through the said thimbles and spring and collars on the said rod whereby the motion of the rod is communicated to the said cylinder.

70 15 20 25 30 35 40 45 50 55 60 65 70 75 80 85 90 95 100 105 110 115 120 125 130

2. The combination of scaffold pole, or poles, movable scaffold, vertical series of holes or detents on the face of the pole, a duplex lever and claw gear on the scaffold and a claw disengaging mechanism all co-operating together as hereinbefore set forth with reference to the lowering of the scaffold.

3. The combination, substantially as herein specified, of the vertical pole or poles provided with holes or detents in vertical series, the movable scaffold sliding upon said pole or poles, the vertical guide-rods $e e$ carried by said scaffold, the slider e^2 guided by said rods and provided with the fulcrum pin e^4 , a lever or levers fulcrumed on said pin and connected with the floor of the scaffold by a link, the claw f^4 carried by a bell-crank lever f pivoted to said slider, the claw f^5 carried by a subjacent bell-crank lever f' , the crutch f^3 connecting said bell-crank lever f' with the floor of the scaffold, and devices for forcing said claws into mesh with said holes or detents, for raising the scaffold in the manner set forth.

10 15 20 25 30 35 40 45 50 55 60 65 70 75 80 85 90 95 100 105 110 115 120 125 130

4. The combination, substantially as hereinbefore specified, of the movable scaffold, the scaffold pole or poles, a rearwardly projecting shifting strut carried by said pole or poles and having the horizontal rollers b^{11} at its extremities, shifting ropes applied to the top of the pole, a base-block in which the pole is pivotally stepped, and means for moving said base-block laterally to complete its adjustment.

5. The combination, substantially as hereinbefore specified, of the movable scaffold, the scaffold pole or poles, the shifting strut projecting rearwardly from said pole or poles and having the horizontal rollers b^{11} and horizontal pivots b^{16} , shifting ropes applied to the top of the pole, a base-block in which the pole is pivotally stepped, and means for moving said base-block laterally to complete its adjustment.

6. The combination, substantially as hereinbefore specified, of the movable scaffold, the scaffold pole or poles, the safety rope b^{18} fixedly held at both ends, rope-clamping devices attaching the top of the pole to said safety-rope, and the rope b^7 connected with said clamping devices for releasing the top of the pole from said safety rope.

In witness whereof I have hereunto affixed

my signature, in presence of two witnesses, to this 28th day of December, 1892.

KARL ALBERT FROSELL.
